UNITED STATES PATENT OFFICE.

ANDREW E. JOHNSON, OF PROVIDENCE, RHODE ISLAND.

FLOOR-SURFACING MACHINE.

No. 927,409.

Specification of Letters Patent.

Patented July 6, 1909.

Application filed June 2, 1908. Serial No. 436,315.

To all whom it may concern:

Be it known that I, ANDREW E. JOHNSON, a citizen of the United States, residing at Providence, in the county of Providence and State of Rhode Island, have invented certain new and useful Improvements in Floor-Surfacing Machines, of which the following is a specification.

My invention relates to improvements in floor-surfacing machines, and it consists in the constructions, combinations and arrangements herein described and claimed.

The object of my invention is to provide a compact and efficient floor-surfacing machine adapted to dress a floor in a uniform and suitable manner under all conditions occurring in practice.

A further object of my invention is to provide an improved floor-surfacing machine capable of being readily and conveniently adjusted by the operator for meeting all conditions of work.

In the accompanying drawings, forming a part of this application and in which similar reference symbols indicate corresponding parts in the several views: Figure 1 is a side elevation, illustrating one embodiment of my invention; Fig. 2 is a detail sectional view, illustrating means for adjusting the machine bed for elevating or depressing the finishing rollers to control their action on the flooring; Fig. 3 is a detail elevation of the upper portion of the handle shown in Figs. 1 and 2; Fig. 4 is a plan view of the adjustable yoke shown in Fig. 2. Fig. 5 is a plan view of the finishing rollers and their driving mechanism, one of the rollers being shown partly broken away; Fig. 6 is a longitudinal section through the bed of the ma-

chine; Fig. 7 is an end view of the pedal shown in Figs. 1 and 6; Fig. 8 is a sectional view on the line 8—8 of Fig. 6, and Fig. 9 is a rear elevation of the finishing rollers and their journal support.

Referring to the drawings, 1 indicates a bed journaled on the front axle 2, which latter has suitable truck wheels 3 rigidly secured on its ends. A rear axle 4 carries truck wheels 5, and is journaled at 6 in an adjustable yoke 7 provided with eyes 8 for pivotally receiving the rod 9 carried by the bed 1.

A tubular handle 10 is shown threaded at 11 in a hollow boss 12 on the bed 1; the upper end of said handle carrying cross-bars 13 constituting convenient hand grasps for

the operator. A burled hand disk 14 presses against the upper end of the handle 10 and is secured to a rod 15 extending from said handle and through an elongated opening 60 16 in the yoke 7; the lower end of said rod 15 being threaded in a nut 17 seated in a recess 18 in the yoke 7. A coil spring 19 encircles the rod 15 and is confined between the opposing faces of the boss 12 and yoke 7; 65 thereby tending to yieldingly maintain the rear end of the bed 1 in elevated position.

The worm wheel 20 is rotatably mounted on the forward axle 2 in mesh with a worm 21 on the stub shaft 22 journaled in the 70 bed 1.

A clutch 23 splined on the axle 2 is shifted by a yoke 24 for locking and releasing the worm wheel 20 relative to said axle. The yoke 24 is secured to a rod 25 journaled in 75 the bed 1, and carrying at its rear end a pedal 26 in convenient position for actuation by the operator for locking or releasing the worm wheel 20 relative to the axle 2.

The dressing rollers 27 are secured to a 80 common shaft 30 which is journaled at 28 in a bracket 29 secured to the forward end of the bed 1. A spindle 31, journaled in the bracket 29, carries the sprocket wheel 32 at its rear end and the bevel gear 33 at its forward end in mesh with a corresponding bevel 34 on the roller shaft 30.

A hood 44 incloses the dressing rollers and is provided with a suitable discharge conduit 45 communicating with the casing 46 of a fan, 90 or other exhaust device; the casing 46 being provided with a discharge pipe 47, to which can be attached a bag, or other receptacle, for receiving the detritus and dust from the finishing rollers.

Any suitable motor and source of energy, such as an electric motor 48 and storage battery 49 with the usual cut-out switches, are shown secured on the bed 1. The drive shaft 50 of said motor is shown connected by a 100 sprocket chain 51 to the wheel 32 for driving the finishing roller, and by a belt 52 to the exhaust fan for actuating the latter. The driving shaft is further suitably connected as by a belt 53 with pulleys 54 on the stub shaft 105 22 for actuating the worm 21 on said shaft.

From the above description, it will be understood that my invention provides an efficient means by which the operator can instantly and conveniently adjust the hand 110 disk 14 for regulating the pressure of the finishing rollers on the flooring and the extent

- of action of said rollers. In this construction, the spring 19 constitutes a yielding resistance for maintaining the dressing rollers with a uniform pressure against the flooring; 5 the inertia of the bed 1 and the parts carried thereby acting very advantageously to deaden the action of the spring 19 and insure a practically constant pressure of the finishing rollers on the flooring.
- 10 It will be obvious that under certain conditions occurring in practice, such as when traveling along a base board, the hood 44 can be quickly removed to permit close approach of the dressing rollers thereto.
- 15 I have illustrated and described a preferred and satisfactory construction, but, obviously, changes can be made in the scope of my invention.

Having thus described my invention, what 20 I claim as new and desire to secure by Letters-Patent is:

1. In a floor-surfacing machine, the combination of a machine bed, a finishing roller carried by said bed, an axle journaled in 25 said bed, bearings adjustably secured to said bed, an axle journaled in said bearings, and means for adjusting said bearings, substantially as described.
2. In a floor-surfacing machine, the combination of a machine bed, a finishing roller carried by said bed, an axle journaled in said bed, bearings adjustably secured to said bed, an axle journaled in said bearings, a tubular 35 handle secured to said bed, and means extending through said handle for adjusting said bearings, substantially as described.
3. In a floor-surfacing machine, the combination of a machine bed, a finishing roller carried by said bed, an axle journaled in said 40 bed, bearings adjustably secured to said bed, an axle journaled in said bearings, a spring confined between said bearings and bed, and

means for adjusting said bearings against the tension of said spring, substantially as described.

4. In a floor surfacing machine, the combination of a machine bed, a finishing roller carried by said bed; an axle journaled in said bed, bearings pivotally secured to said bed, an axle journaled in said bearings, resilient 50 means confined between said bed and bearings, a handle secured to said bed, and adjusting means engaging said handle and threaded in said bearings, substantially as described.

5. In a floor-surfacing machine, the combination of a machine bed, a finishing roller carried by said bed, a front axle journaled in said bed, bearings pivotally secured to said bed, a rear axle journaled in said bearings, 60 means for adjusting said bearings, a motor carried by said bed, and clutch mechanism for operatively connecting said motor to said front axle and finishing roller, substantially as described.

6. In a floor-surfacing machine, the combination of a machine bed, a finishing roller carried by said bed, an axle journaled in said bed, bearings pivotally secured to said bed, an axle journaled in said bearings, a tubular 70 handle secured to said bed, a rod extending through said tubular handle and threaded in said bearings, a hand disk secured to said rod in engagement with the top of said handle, and a spring encircling said rod in engagement with said bearing, substantially as described.

In testimony whereof I affix my signature in presence of two witnesses.

ANDREW E. JOHNSON.
